UNITED STATES PATENT OFFICE.

FRED H. MCCOY, OF BURLINGTON, VERMONT.

SEAM.

1,426,892.

Specification of Letters Patent. Patented Aug. 22, 1922.

Application filed August 30, 1920. Serial No. 406,743.

To all whom it may concern:

Be it known that I, FRED H. MCCOY, a citizen of the United States, residing at Burlington, in the county of Chittenden and State of Vermont, have invented certain new and useful Improvements in Seams, of which the following is a specification.

My invention is an improvement in seams, and pertains particularly to artificial lap 10 seams, and is a continuation in part of my application on combined folder for sewing machines, Serial #156,188, filed March 20, 1917, which has matured into Patent #1,357,105.

18 In the manufacture of garments it has been found that in order to provide shape and proper "hang," it is necessary to cut the fabric or material into a certain number of pieces and to join the several pieces by 20 seams, of which there are as few as possible in order to preserve the appearance of the garments and to save material, and yet secure the reinforcement and stability which seams afford.

25 In the manufacture of the so-called "two seam" overall, it has been customary to cut two pieces, a front and a back, for each leg. After cutting, the pieces are given to one operator, who fells the two pieces on a 30 "flatbed" machine, and they are then transferred to a second operator who fells the two remaining edges on a "cylinder bed" machine.

As is well known, there is a loss of material every time it is cut, and in the illustration given, besides the loss occasioned by the cutting, there is the extra loss caused by the use of the extra operative and extra machine.

40 Bearing in mind the desirability of fewer cuts in fabric, and the necessity for strength and shape of the garments, as well as the advantages of reducing labor costs as far as possible, the main objects of my invention 45 are; to cut the cost of manufacture by saving material, without affecting the quality of the garments, either as to shape, strength, or wearing qualities, and, to reduce the overhead in factories by eliminating excess 50 labor and machine costs.

In carrying out my invention, which may be applied to any garments or fabric although primarily adapted to the manufacture of overalls, I utilize an artificial lap 55 seam, formed by folding material along desired lines, and then stitch the free edges or

loops of the fold to the material be a plurality of rows of stitches, so that the appearance of a real lap seam is simulated, and the cutting of material to form a real 60 seam at the desired place is eliminated.

In the manufacture of certain articles, such as shirt waists, it is necessary to slit the material part way, or to cut out a portion so that a bifurcation results. It has been 65 customary to fell the two edges so that a seam is formed, running only to the end of the bifurcation, and presenting a very unsightly appearance.

I have found that the appearance of the 70 article is enhanced, and the article is strengthened, if the seam is continued through the body of the article, instead of stopping at the bifurcation end. This is done by prolonging the real seam into an 75 artificial seam, with the same rows of stitching on both the real and the artificial seam, giving the appearance of a real continuous seam which is partly real and partly artificial.

The range of applications of my invention are illimitable, although I have found the greatest utility in the manufacture of 80 overalls, where I have effected great savings.

In the accompanying drawings, forming a part of my application:

Fig. 1, is an elevation of a coat constructed in accordance with my invention, the coat 90 having cuffs on the sleeve;

Fig. 2, is a section through the cuff, taken on line 2—2 of Fig. 1, and showing the construction thereof;

Fig. 3, is an elevation of a portion of a 95 sleeve and a cuff thereon, as made before my invention;

Fig. 4, is a section on line 4—4 of Figure 3 showing the construction of the cuff;

Fig. 5, is a detached perspective view of a 100 portion of the back of the coat shown in Fig. 1, and taken on the line 5—5 thereof;

Fig. 6, is an elevation, partly in section of the combined feller and feller member used in producing the artificial lap seam;

Fig. 7, is a plan view of the two pieces of 105 material, partially broken away, used in producing a leg and peg top effect in accordance with the present practice in manufacturing;

Fig. 8, is a plan view partially broken 110 away of the one piece of material used in making a leg of a garment according to

my invention, with a slit in the material for forming the "peg top" effect;

Fig. 9, is an elevation of the upper part of a pair of trousers made from one piece of material for each leg as shown in Fig. 8, and disclosing an apparently real lap seam extending from the waist down the side of the leg;

Fig. 10, is a section on line 10—10, of Fig. 9, disclosing the artificial lap seam on the side of the leg, and

Fig. 11, is a perspective view of a portion of the piece of material shown in Fig. 8, looking from the bifurcated end and showing how the "peg top" effect is attained by the real lap seam at the top of the trousers, merging into the artificial lap seam extending down the leg, or the artificial seam merging into the real seam.

As illustrated by Fig. 1, the back of the coat made in accordance with my invention has a back formed of one piece of material 13, having a vertically extending artificial lap seam 14 formed in the middle thereof, in lieu of the customary two pieces joined by a real lap seam.

This artificial lap seam is formed preferably on some such device as illustrated in Fig. 6, which is described and claimed in my aforementioned application #156,188, and which consists essentially of a feller 15, of usual construction upon which real lap seams are felled, and a feller member 16, with cooperating creaser arm 17, to fold the material, and a stitching unit 18 arranged in the paths of delivery of both the feller and feller member so that a plurality of rows of stitches are put in the fold of the material to fasten it down. It is to be noted that the stitching unit sews goods delivered from either the feller or feller member. This enables me to sew two raw edges together on the feller, to form the well known interlocked seam shown for instance in patent to Beals, #614,824, and then to continue the seam into an artificial lap seam where there are no edges but an unbroken expanse of material, such for instance as when working on the material shown in Fig. 8.

The coat has a front piece 19, on both sides, which pieces are joined to the back, effected by the change in construction permitting a real lap seam 20. Obviously there is a saving of material at the elimination of a two piece back.

The sleeve 21 is formed from two pieces of material joined at their raw edges by seams 22, as is customary, and having a cuff 23, formed at the lower end. By my invention this cuff is made by running the sleeve through the feller member and making an artificial lap seam extend transversely of the sleeve, as shown by 24.

The old method of making a cuff is illus-

trated by Figs. 3 and 4, in which the sleeve 21', has a cuff 23' stitched to it. Here again I effect a saving by the elimination of the extra piece of material necessary to form the attached cuff.

The old method of making trousers by forming each leg of two parts 25, besides necessitating an extra cutting of material, also required extra machines and operatives. I form each leg of a single piece 26, of material, having a slit 27 formed or cut in it, and sew the raw edges of the slit on the feller 15, forming a real lap seam thereof, and then slide the material up into the felling member and continue the seam to the end of the leg. It is to be noted that this seam 29 is apparently a real continuous lap seam, but is in reality partly real and partly artificial. By cutting the slit 27 with curved edges 28, a rounded effect is produced for giving a "peg top" to the trousers. It will be apparent that I may sew two raw edges of any piece of material, and then continue the seam into an artificial seam, such as putting darts in shirtwaists, in which a slit is made to extend but a short distance into the material in order to give a gathered effect, this may be made much more slightly by continuing the seam into an artificial seam, as it gives a finish unobtainable by a seam running but part way into a garment and then stopping.

It is immaterial whether the two edges of the bifurcation be joined by a seam first, and then the unslit portion be folded, as obviously the folding of the unslit portion might be accomplished first, and then the edges of the bifurcation be joined, and I therefore do not wish to be considered as limited to the particular order of formation of the seams disclosed herein.

I claim as my invention:

1. As an article of manufacture, a piece of material having a seam, one part of the seam being formed by the joining together of two edges of the material, and another part of which seam is formed beyond said edges by folding the material.

2. As an article of manufacture, a piece of material having a seam, one part of the seam being formed by the joining together of two edges of the material with a folded and interlocked seam, and another part of which is formed beyond the two edges by folding the material.

3. A method of seaming a piece of fabric that has a slit cut in it which consists in joining the two edges of the slit by a real lap seam, and continuing the seam into the body of the uncut fabric by folding the fabric and stitching the free edges of the fold to the body of the fabric to form an artificial lap seam, resulting in an apparently real continuous lap seam which is partly real and partly artificial.

4. As an article of manufacture a piece of material having a seam, one part of the seam being formed by the joining together of two edges of the material, and another part of 5 the seam being formed beyond the edges by folding the material, and a continuous series of stitches extending along the seam.
5. A method of seaming material in which there is a slit, which consists in joining the 10 edges of the slit and folding the unslit portion of the material in substantial alignment with the slit to form a continuous seam.
6. A method of seaming material in which there is a slit which consists in folding, interlocking and joining the edges of the slit 15 and folding the unslit portion in substantial alignment with the slit to form a continuous seam.
7. A method of seaming material in which there is a slit which consists in joining the 20 edges of the slit and folding the unslit portion in substantial alignment with the slit, securing the joint and fold by a continuous series of stitches to form a continuous seam.

In testimony whereof I affix my signature. 25
FRED H. McCOY.

Certificate of Correction.

It is hereby certified that Letters Patent No. 1,426,892, granted August 22, 1922, upon the application of Fred H. McCoy, of Burlington, Vermont, for an improvement in "Seams," were erroneously issued to the inventor, said McCoy, whereas said Letters Patent should have been issued to *Mead Manufacturing Company, of Burlington, Vermont, a Corporation of Vermont*, said corporation being assignee of the entire interest in said invention, as shown by the records of assignments in this office; and that the said Letters Patent should be read with this correction therein that the same may conform to the record of the case in the Patent Office.

Signed and sealed this 19th day of September, A. D., 1922.

[SEAL.]

WM. A. KINNAN,

Acting Commissioner of Patents.
